UNITED STATES PATENT OFFICE

MAX W. GOLDBERG, OF PORT WASHINGTON, WISCONSIN, ASSIGNOR, BY MESNE ASSIGNMENTS, TO MODERN EQUIPMENT COMPANY, OF PORT WASHINGTON, WISCONSIN, A CORPORATION OF WISCONSIN

SWIVEL SUPPORTING MEANS FOR ELECTRICALLY OPERATED DEVICES

Application filed December 30, 1929. Serial No. 417,582.

This invention relates to improvements in swivel supporting means for electrically operated devices.

This application is a continuation in part 5 of application for automatic pouring devices, Serial No. 390,058, filed September 3rd, 1929.

It is one of the objects of this invention to provide an improved swivel supporting means for electrically-operated devices which

10 has means for conducting current from an overhead trolley to the device to be operated, the said means permitting swiveling of the device without interfering with the passage of the electrical current.

15 A further object of this device is to provide a swivel supporting means for electrically operated devices which is simple in construction, efficient in operation and well adapted for the purposes described.

20 With the above and other objects in view, the invention consists of the improved swivel supporting means for electrically operated devices and all its parts and combinations as set forth in the claims, and all equivalents 25 thereof.

26 In the accompanying drawing, illustrating one complete embodiment of the preferred form of the invention, in which the same reference numerals designate the same parts in all of the views:

30 Fig. 1 is a side view of the device, showing it in attachment with an overhead rail and trolley, parts being broken away;

35 Fig. 2 is a rear view thereof, the overhead rail being shown in section;

Fig. 3 is an enlarged detail view of a portion of the device, parts being broken away;

40 Fig. 4 is a sectional view taken on line 4—4 of Fig. 5; and

Fig. 5 is a sectional view taken on line 5—5 of Fig. 3.

45 Referring to the drawing, the numeral 10 designates a supporting portion having a central bearing 11 and having supporting arms 12 extending upwardly from each end thereof, each of said arms being forked. A pair of rotatably mounted wheels 13 is carried by each of said arms, and the wheels are adapted to ride along an overhead rail 14. Secured to one end of the supporting member

10 and extending transversely thereof is a bar 15 on which slotted members 16 are slidably mounted. Trolley poles 17 have their lower ends yieldingly pivoted to the upper portions of the members 16 as at 18, and have their upper ends forked as at 19 to receive rotatably mounted trolley wheels 20. The said trolley wheels each engage trolley wires 21.

Within the bearing portion 11 of the supporting member 10 is a tubular member 22 which has an enlarged upper section, and which has a lower threaded portion 23 and an upper threaded portion 24. Nuts 25 and 26 are threaded on the portions 23 and 24, respectively. The enlarged section of the tubular member is also provided with an annular shoulder 27. Positioned between said shoulder 27 and the nut 25 is an insulating sleeve 28. Rings 29, which surround said sleeve, are formed of a suitable electrical conducting material. The said rings are spaced apart by insulating rings 30. Loosely positioned between the shoulder 27 and the nut 26 is a sleeve 31 having an enlarged upper 70 end portion 32 formed with an annular groove 33 therein. Balls 34 are positioned within the groove between the upper end of the sleeve 31 and the nut 26. The said sleeve 31 is positioned within the bearing portion 75 11 of the support 10. The enlarged portion 32 of said sleeve rests on the upper end of said bearing 11 and prevents downward movement of the tubular member, and also provides a swivel connection for the latter. 80

Secured to and extending from the lower portion of the support 10, at one end thereof, is a contact block 35 having a plurality of bores 36 therein, within which contact fingers 37 are slidably positioned. The said contact fingers have their inner ends engaging coiled springs 38 in the usual manner, and have their outer ends engaging the ring-shaped contacts 29 which are carried by the tubular member 22.

90 The trolley poles 17 are connected by wires 39 with the contact fingers 37. The said fingers, which frictionally engage the rings 29, conduct electricity from the trolley there- 95 to. The enlarged upper portion of the tubu- 100

lar member 22 is formed with grooves 40, and within said grooves wires 41 are positioned.

The said wires have one end soldered or otherwise connected to the contact rings, and the other end extending to a starter box 42.

6 The lower end of the tubular member 22 may be provided with a hook 43, by means of which any desired electrical device may be supported, the said device being adapted to have wires 44 which extend from the starter box connected thereto to supply the necessary current.

10 In use of the device any desired electrical mechanism may be suspended from the hook 43. The said mechanism may be an electrically operated pouring device. By means of the overhead rail and trolley, the device may be moved to the desired part of the foundry or other building in which it is being used, 15 and it may then, by means of the swivel connection within the bearing 11, be rotated to a desired angular position. Due to the novel combination of the rotary contact with an overhead supporting means, this swiveling 20 operation may be performed without in the least interfering with the conducting of electricity from the overhead trolley to the machine.

25 Although only one form of the invention 30 has been shown and described, it is not desired to be limited to this exact showing, as the broad concept of the invention includes all changes and modifications as may fairly come within the scope of the claims.

35 What I claim is:

1. A supporting means for electrically operated devices, comprising an overhead track, a movable frame member having electrical conducting means in connection therewith 40 and entirely suspended from said track, a supporting member for an electrically operated device pivotally suspended from said frame member, electrical conducting means in connection with said supporting member, 45 and means for conveying electricity from the conducting means of said frame member to the conducting means of said supporting member, without interfering with the pivotal movement of the latter on the frame.

50 2. A supporting means for electrically operated devices, comprising an overhead rail, a frame movable along said rail and entirely suspended therefrom, a supporting member for an electrically operated device 55 pivotally suspended from said frame, trolley wires extending parallel to said rail for conducting electricity from an outside source, trolley poles in connection with said frame member engaging said trolley wires, contact 60 rings carried by the supporting member, and brush members carried by the frame and in connection with the trolley poles, said brush members frictionally engaging the contact rings on the supporting member to conduct 65 electricity thereto without interfering with

pivotal movement of the supporting member on the frame.

3. A supporting means for electrically operated devices, comprising an overhead rail, a frame movably suspended from said rail, a bearing mounted in said frame, a supporting member for an electrically operated device revolubly mounted in said bearing, a suspending member carried by a lower portion of said supporting member, a trolley 70 wire extending parallel to said rail for conducting electricity from an outside source, a trolley pole carried by said frame and engaging said trolley wire, contact rings surrounding said supporting member, and brush members carried by the frame and electrically connected with said trolley pole, said brush members frictionally engaging the contact rings on the supporting member to conduct electricity thereto 75 without interfering with pivotal movement of the supporting member with respect to the frame.

In testimony whereof, I affix my signature.

MAX W. GOLDBERG.
